CIRCUIT INTERRUPTING DEVICE

Filed Feb. 4, 1928

Inventor:
Joseph W. Owens,
by *Charles V. Yuller*
His Attorney.

UNITED STATES PATENT OFFICE

JOSEPH W. OWENS, OF SCHENECTADY, NEW YORK, ASSIGNOR TO GENERAL ELECTRIC COMPANY, A CORPORATION OF NEW YORK

CIRCUIT-INTERRUPTING DEVICE

Application filed February 4, 1928. Serial No. 251,987.

This invention relates to circuit interrupting devices and more particularly to a detachable arc barrier arrangement for multipole electric switches and the like.

5 The principal object of the present invention is to provide an improved mounting for the arc barriers that will enable the barriers to be mounted and demounted without the use of tools. In this way the barriers may be 10 easily removed to permit access to the arcing contacts of the circuit interrupter for wiring or inspection and repair.

The improved arc barriers of the present invention are particularly advantageous in 15 multipole electric switches which are mounted within an inclosing casing. With such switches it is desirable that the arc barriers located between the adjacent poles of the switch be readily removable without necessitating the removal of the switch mechanism from the inclosing casing. Heretofore it has been the common practice to secure the arc barriers to the base upon which the switch contacts are mounted by means of screws or 20 other fastenings accessible only from the back of the base. Hence with such mounting of the arc barriers it is necessary to unwire and remove the entire switch mechanism from the inclosing casing before the arc barriers may 25 be removed. Moreover, the arc barriers must be secured in place before the switch mechanism is mounted in the inclosing casing and thus prevent free and convenient access to the switch contacts during wiring or inspection 30 and repair operations. In addition the metallic screw fastenings for the arc barriers tend to weaken the insulating properties and cause the arc to strike through the barriers.

The present invention enables the arc barriers to be readily mounted between the adjacent poles of the switch after the base with the switch mechanism thereon is mounted within the inclosing casing and the wiring operation is entirely completed. Likewise, 45 the arc barriers may be readily removed and replaced at any time it is necessary to repair or inspect the switch parts. In addition, with the present invention the arc barriers may be moulded of arc-resisting material, such for 50 example, as an asbestos compound, having a

unitary structure provided with locking projections whereby the arc barriers are mounted or supported in their operative position between the poles of the switch mechanism without any metallic fastenings whatever.

55 In carrying the present invention into effect in a preferred form the arc barriers are formed preferably of moulded arc-resisting material and provided with projecting locking keys adapted to cooperate with suitable locking holes in the base upon which the switch mechanism is mounted. The arrangement is such that the locking keys upon the arc barriers may be inserted in the locking holes formed in the base and the barrier moved laterally with respect to the base to bring the 60 keys into locking engagement with the keyholes. Upon reverse lateral movement of the arc barriers the locking engagement is released to permit removal of the arc barriers. 65 In addition, the arc barriers preferably have formed integral therewith projecting shoulders or shields which serve to cover the locking holes formed in the base and thereby effectively block the passage of the arc through 70 the holes formed in the base.

75 In the accompanying drawing Fig. 1 shows a three-pole electric switch mounted in an inclosing casing and provided with the improved form of arc barriers, one of the barriers being removed and certain parts of the switch mechanism and casing being broken away to reveal the details of construction. Figs. 2 and 3 are front and reverse perspective views of the unitary moulded arc barrier 80 showing the detailed form of the locking keys and the shoulders formed thereon.

85 As shown in Fig. 1, the three-pole switch is of the improved type described and claimed in the copending patent application of Louis 90 J. Weber, Serial No. 241,950, filed December 22, 1927, and assigned to the assignee of my present invention, patented December 31, 1929, No. 1,742,109. The three-pole switch mechanism is mounted upon the base 10 95 which, in turn, is mounted within the inclosing casing 11. Each pole of the three-pole switch mechanism consists of a set of spaced apart stationary contacts 12 which are mounted directly upon the base 10 and a cooperat- 100

ing bridging contact 13 which is yieldingly mounted upon a movable switch arm 14. The three movable switch arms are fixedly secured to an operating member 15 which is 5 rotatably supported in the bearings 16 and 17.

In order to prevent arcing between the adjacent poles of the switch, provision is made for mounting an arc barrier 20 on the base 10 between the adjacent sets of stationary contacts 12. The arc barriers 20 are formed 10 of good arc-resisting material such as, for example, moulded asbestos compound, and are of suitable dimensions to effectively isolate the arcs occurring at the adjacent poles 15 of the switch.

In accordance with the present invention, each of the arc barriers 20 is arranged to be 20 removably mounted on the base 10 of the switch mechanism so as to be readily removable from the front of the panel without the use of tools. This is accomplished by providing a pair of keyhole shaped openings 21 and 22 in the base 10 for each arc barrier. The arc barriers in turn are provided on one 25 side with a pair of projecting locking keys 23 and 24 adapted to be received in and interlocked with the openings 21 and 22. As more clearly shown in Figs. 2 and 3, the locking keys 23 and 24 have projections 25 on either 30 side so as to interlock with the narrow portions 26 of the key-hole shaped openings 21 and 22. The projections 25, however, are of suitable dimensions to pass through the enlarged portion 27 of the key-hole shaped 35 openings in the base.

It will be evident that after passing the shoulders 25 through the enlarged portion of the key-hole openings, the barrier may be slid downward to bring the projections 25 40 into interlocking engagement with the narrow portions of the openings and thereby firmly secure each of the arc barriers in operative position on the base 10 between the poles of the switch. In order to insure that 45 the arc barriers are not accidentally displaced from the interlocked position by extraneous vibration or during handling of the switch a spring 28 preferably is located at one side of the key-hole shaped openings in the base 50 10 so as to frictionally engage with the locking key on the arc barrier. It will be observed in Fig. 1 that the upper key-hole shaped openings 22 in the base 10 are not closed at the top. It will be evident, however, that in case the base 10 were extended 55 the key-hole shaped openings 22 would be of substantially the same shape as the openings 21, except for the provision of the locking spring 28, the mounting of which requires a narrow slot 29 extending from the 60 narrow portion of the opening 22.

In order to prevent the arc passing through the enlarged portions of the locking openings in the base 10 when the arc barriers are mounted in operative position, suitable

shoulders 30 and 31 are provided on either side of the barrier 20 of sufficient width to cover completely all the openings in the base. The shoulder 31 extends across the full width of the arc barrier so as to cover the slot 29, 70 as well as the right hand edge of the enlarged portion of openings 21 and 22. The shoulder 30 serves to cover the left hand edge of the enlarged opening 21.

With the base 10 mounted within the 75 enclosing casing 11 and the arc barrier 20 in operative position between the poles of the switch mechanism as indicated in Fig. 1, the arc barriers may be readily removed by sliding the barrier bodily upward until the interlocking shoulders 25 are moved out of engagement with the narrow portion of the key-hole openings. Thereupon the barrier 20 may be freely withdrawn out of engagement with the base 10. To replace the barrier it is 80 only necessary to reverse the operations just described.

Thus it will be seen that the present invention provides an arc barrier construction that 85 permits the barriers to be mounted and demounted at will and without the use of any tools. In addition, the barriers being formed as a unitary structure of arc resisting material without any metallic fastenings required for their support, there is full insulation 90 between the adjacent poles of the switch which effectively isolates the arcs appearing at each 95 of the poles.

What I claim as new and desire to secure by Letters Patent of the United States, is:— 100

1. In a circuit interrupter, the combination of a base having arcing contacts mounted thereon and having key-hole-shaped openings formed therein and an arc barrier having projecting keys operable into and out of 105 interlocking engagement with the openings in the base upon predetermined relative movement of the barrier with respect to said base.

2. In a circuit interrupter, the combination of a base having arcing contacts mounted thereon and having key-hole-shaped openings formed therein and an arc barrier having projecting keys operable into and out of 110 interlocking engagement with the openings in the base upon predetermined relative movement of the barrier with respect to said base and having shoulders for covering the enlarged portions of the key-hole shaped 115 openings in the base when the barrier is 120 mounted in operative position.

3. In a circuit interrupter, the combination of a base having arcing contacts mounted thereon and having key-hole-shaped openings formed therein, an arc barrier having 125 projecting keys operable into and out of interlocking engagement with the openings in the base upon predetermined relative movement of the barrier with respect to said base, and a resilient locking member for maintain- 130

ing the arc barrier in interlocked engagement with the base.

4. A multipole electric switch comprising a base having a plurality of switch contacts in spaced alignment thereon and having key-hole-shaped openings formed in the base between said contacts, a plurality of arc barriers for mounting in said openings, said barriers each having projecting keys formed on one edge thereof and operable into and out of interlocking engagement with the openings in the base upon predetermined relative movement of the barrier with respect to said base and having shoulders for covering the corresponding openings in the base when the barrier is mounted in operative position.

In witness whereof, I have hereunto set my hand this 3rd day of February, 1928.

JOSEPH W. OWENS.
